FEED MIXER

Albert E. Anderson, Quincy, Ill.

Application May 3, 1948, Serial No. 24,714

7 Claims. (Cl. 259—7)

1

This invention relates to a feed mixer.

An object of this invention is the production of an efficient and novel machine which will mix molasses into dairy feeds after said feeds have been first mixed in a dry state, in a regular feed mixer and made ready for the molasses.

It is to be understood that feed is spouted from the regular sacking spout of the main mixer into the upper chamber of the pre-mixer, where it is met by a stream of molasses. The two then pass downwardly, by force of gravity, and are mixed and commingled thoroughly before entering back into the main mixer.

Another object of this invention is the construction of a novel apparatus which can be used in conjunction with main mixers provided with a loading hopper, either above or below the floor; this is accomplished by the extreme compactness of my invention and its powerful and complete mixing agitation, requiring much less power than ordinary mixers for a similar purpose.

A still further object of this invention is the production of a mixer that is portable so that it can be operated by one man to quickly and easily move to and from the main mixer. It is to be understood that the main mixer may be utilized for mixing feeds other than those containing molasses, at which time the pre-mixer must be removed while sacking from the spout of the main mixer.

Another object of the invention is to mount the pre-mixer cylinder or tube at a high angle above the horizontal and below the vertical, whereby the machine can be driven by a motor without using belts or pulleys, and yet operating with high efficiency.

A still further object of the invention is to so construct the apparatus whereby the mixer body is suspended from a bar, allowing the mixer body to pivot and swing to enable the apparatus to be slipped into an operative position with respect to the loading hopper of a conventional feed mixer.

With the foregoing and other objects in view, this invention comprises certain novel constructions, combinations, and arrangements of parts as will be hereinafter fully described, illustrated in the accompanying drawings, and more particularly pointed out in the appended claims.

In the drawings:

Figure 1 is a view in side elevation of an apparatus constructed in accordance with the present invention, showing same assembled with a conventional feed mixer.

Figure 2 is a vertical, longitudinal, sectional view through the apparatus.

Figure 3 is a rear view in elevation.

Figure 4 is a view in side elevation of the apparatus, showing the washing tank.

Figure 5 is a horizontal, sectional view, taken

2

on line 5—5, Fig. 2, and looking in the direction of the arrows.

Figure 6 is a horizontal, sectional view, taken on line 6—6, Fig. 2 and looking in the direction of the arrows.

Referring to the drawings, in which I have shown the preferred embodiment of this invention, 1 designates a conventional feed mixer, which is provided with the auger tube 2 and the feed mixer spout 3.

The novel apparatus of this invention comprises a frame, including side bars 4 and rear legs 5. A handle 6 has the lower ends of side bars 4 fixedly secured thereto. Each side portion 7 is bent upwardly at 8, and on this bent up portion 8 is a roller or a wheel 9. Therefore, when the apparatus is at rest, Figs. 1 and 2, the bent portions 8 will be engaging the support and the apparatus will be held stationary. The handle 6 extends beyond the rear legs 5. The rear legs 5 are connected by two horizontal bars 10 and 11. A mixing tube 12 is provided, which is open at its lower end (Fig. 2). The mixing tube 12 is closed at its upper end, and is provided with an outwardly extending feed spout 13. This feed spout 13 is open at an angle so as to fit snugly against the bottom end of feed mixer spout 3, as shown in Figure 1. The feed spout 13 is provided with a dry feed by-pass aperture 14. This aperture 14 permits a percentage of dry feed to by-pass the molasses-mixing chamber to keep the wet feed from adhering to the auger. A shaft 15 extends through the sides of flanged shield 16, and the ends of shaft 15 are

30 in the side bars 4. The flanged shield 16 partly surrounds the electric motor 17, as well as supports the base 18 on which the motor 17 is mounted. The lower portion of the shield 16 is suitably secured to the upper portion of the mixer tube 12. Therefore, it will be seen that the tube 12, shield 16, and motor 17 have a pivotal or swinging movement on the shaft 15.

Within the mixer tube 12 is a stirrer shaft 19 on which is mounted the beaters 20; these beaters are positioned at an angle and are staggered, whereby they wipe the tube 12 clean when operating. A molasses supply pipe of tube 21 extends into the top portion of mixer tube 12, as clearly seen in Figure 2.

50 In operation, the handle 6 is grasped and moved upwardly so that the wheels 9 engage the floor or platform, whereupon the operator can quickly move the apparatus, as desired. In positioning the apparatus, as shown in Figure 1, the lower end of the mixing tube 12 is swung upward to clear the top of the loading hopper 22, and then it is moved downwardly, by being pivoted on shaft 15, permitting the feed spout 13 to be positioned under spout 3. By reason of the peculiar construction of this apparatus, this

positioning can be quickly accomplished. Likewise, when it is desired to remove the apparatus from an assembled position with the conventional feed mixer 1, the same can be accomplished with equal ease.

It is to be understood that beater arms 20 are both staggered and set into shaft 19 at an angle, so that the tips thereof have a wiping effect on the inner walls of the tube 12. This tends to keep the walls quite clean of adhering molasses and lessens the frequency of washing.

In Figure 4, there is shown a washing tank 23. The water is usually maintained in said tank to the height of line 24. The tank 23 is provided with hooks 25 on its rear portion, which hooks 25 are placed over the two bars 10 and 11. A hook or flange 26 is on the bottom of tank 23 and engages a loose bar 27. The weight of the tank holds the loose bar 27 against the side bars 4 and against the inner face of the flange or hook 26, whereby the tank is maintained in a horizontal position. This tank can be quickly applied to the apparatus, or removed therefrom, as the operator desires.

The shaft 19 is rotated by means of motor 17.

Usually the feed is passed down through spout 3 into spout 13 and thence to the mixer tube, where said feed is impregnated with molasses that is thoroughly mixed by the novel stirrers, the whole mass moving downwardly by gravity to the lower end of the tube 12, and thence into the loading hopper 22, from where the feed is taken up through the auger tube 2 into the upper part of the conventional feed mixer.

The upper beater in the mixer acts as a power-meter which meters the feed into the machine and when the rotor stops, the feed ceases to flow thru machine. Each revolution of the beater arm shakes a given amount of feed down thru mixing chamber so as to maintain a fixed, or adjustable ratio of quantity between the liquid and the dry materials. This is important in that it makes it possible to produce a uniform mixture as to percentage of molasses used.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. In an apparatus of the class described, the combination with a support, of a frame, said frame comprising rear legs and side bars, a handle extending rearwardly beyond said rear legs, said side bars being secured to portions of said handle, said handle provided at its front end with upwardly curved portions, wheels mounted on said upwardly curved portions, whereby when the apparatus is operating, said wheels will be off the support, a mixer tube, said mixer tube being pivotally supported at its upper end on said frame to move between a normal forwardly and downwardly inclined position and a horizontal position for clearing the edge of a loading hopper, stirring means in said mixer tube, and said mixer tube provided with a feed spout.

2. In an apparatus of the class described, the combination of a frame provided with side bars, a mixer tube between said side bars, said mixer tube provided with a shield extending upwardly from the tube at its upper end, a shaft extending

through said shield and mounted upon said side bars, said mixer tube pivoted upon said shaft, stirring means in said mixer tube, said mixer tube provided with a feed spout and a motor driving said stirring means and forming a counter-balance for said tube and stirring means.

3. In an apparatus of the class described, the combination with a frame, of a mixer tube, said mixer tube provided on its upper end with a flanged shield, a shaft extending through the flanges of said shield and into portions of said frame, said mixer tube pivoted upon said shaft, a motor base secured within said shield, a motor mounted on said motor base, stirring means in said mixer tube and connected to said motor, means for supplying a liquid through said mixer tube, and said mixer tube provided with a feed spout.

4. In an apparatus of the class described, the combination with a frame, of a mixer tube pivotally mounted at its upper end on said frame, a stirrer shaft provided with beaters, said stirrer shaft and beaters within said mixer tube, a supply spout provided near the upper end of said tube, means for admitting molasses near the upper end of said tube, the lower end of said tube provided with a feed discharge opening, a motor and means attaching said motor to the upper end of said beater shaft, means projecting from said tube above the pivotal axis of the tube and having said motor mounted thereon to effect counter-balancing of the tube and beaters, a water tank, means attaching said water tank to said frame, said water tank enveloping the lower portion of said mixer tube, said tank causing the lower end of said tube and the lower beaters therein to be submerged in water when said tank is partly filled with water, and means provided for operating the motor and rotating the beaters while thus submerged.

5. In an apparatus of the class described, the combination of a frame, said frame provided with horizontal bars, a water tank, said water tank provided with means engaging said bars for partly supporting said water tank upon said frame, said frame provided on its front end with a loose bar, means on said water tank engaging said loose bar for partly supporting said water tank, and said frame provided with mixing means extending into said water tank.

6. In an apparatus of the class described, the combination of a frame, said frame provided with a rear end and a front end, fixed means for supporting a water tank on said rear end of said frame, detachable tank supporting means on the front end of said frame, a water tank within said frame, said water tank provided with means engaging said fixed and detachable supporting means, and said frame provided with mixing means extending into said tank.

7. In an apparatus of the class described, the combination of a frame, provided with a rear end and a front end, said rear end provided with a plurality of bars fixedly secured to said frame, said front end provided with a loosely mounted bar, a water tank within said frame, said water tank provided on its rear with hooks over said fixed bars, said water tank provided with a flange on its bottom engaging said loosely mounted bar, and mixing means mounted on said frame and extending into said water tank.

ALBERT E. ANDERSON.
